[57] CLAIM

The ornamental design for a pocket clothes brush, as shown and described.

DESCRIPTION

FIG. 1 is an end elevational view of a pocket clothes
brush, showing my new design;

FIG. 2 is a top perspective view thereof, shown with
the brush portion in the extended position;

FIG. 3 is a top perspective view thereof, shown with
the brush portion in the retracted position;

FIG. 4 is a bottom perspective view of the device as it appears in FIG. 2.
